DESCRIPTION

FIG. 1 is a perspective view of a speaker housing showing my new design;

FIG. 2 is a front elevational view thereof;

FIG. 2 is a front elevational view thereof,
FIG. 3 is a side elevational view thereof, the opposite side

elevational view being a mirror image thereof;

FIG. 4 is a rear elevational view thereof; and

FIG. 5 is a top plan view thereof.
The broken line showings of the bottom pads, the oval area on the rear side, the protruding elements and the circular area on the front side are for illustrative purposes only and form no part of the claimed design.

THE INFLUENCE OF THE CULTURE OF THE PARENTS ON THE CHILD'S LANGUAGE DEVELOPMENT
